UNITED STATES PATENT OFFICE.

CHARLES ROBBINS, OF PHILADELPHIA, PENNSYLVANIA, ASSIGNOR TO THE CUTTER ELECTRICAL AND MANUFACTURING COMPANY, OF NEW JERSEY.

DESIGN FOR A BRUSH FOR ELECTRIC SWITCHES.

SPECIFICATION forming part of Design No. 27,393, dated July 20, 1897.

Application filed June 12, 1897. Serial No. 640,584. Term of patent 7 years.

To all whom it may concern:

Be it known that I, CHARLES ROBBINS, of the city and county of Philadelphia, State of Pennsylvania, have invented and produced a new and original Design for a Contact-Brush for Electric Switches, of which the following is a specification.

In the accompanying drawings, Figure 1 is a plan view of the said brush. Fig. 2 is a perspective view of one side of the same. Fig. 3 is a perspective view of the reverse side of the same.

The leading and characteristic feature of my design is the curved configuration of the contact-brush, the outer circumference 7 of which is approximately in the line of a quadrant. The inner circumference 8 begins at the upper end in the line of a circle approximately concentric with that of the outer mar-

gin, but upon its approach downward toward the base assumes a nearly vertical direction, making the lower portion of the said contact-brush broader than the upper portion. The lower end 6, of still greater width, is bent into a plane at right angles to the main portion. The upper end 9, by a slight double bend, lies in a plane slightly out of but parallel with that of the main body of the said contact-brush.

I claim—

The design for a contact-brush for electric switches, substantially as herein shown and described.

CHAS. ROBBINS.
